P. A. SCHLEMP

NECKTIE FRAME

Filed April 24, 1924

INVENTOR

P. A. Schlemp

BY

J. Ledermann

ATTORNEY

UNITED STATES PATENT OFFICE.

PAUL A. SCHLEMP, OF NEW YORK, N. Y.

NECKTIE FRAME.

Application filed April 24, 1924. Serial No. 708,641.

To all whom it may concern:

Be it known that I, PAUL A. SCHLEMP, a citizen of the United States, residing at New York, in the county of New York and 5 State of New York, have invented certain new and useful Improvements in Necktie Frames, of which the following is a specification.

The main object of this invention is to 10 provide an accessory to dress, and constitutes a frame upon which a four-in-hand knot is formed with a necktie before the latter has been placed on the collar.

Another object is to provide a modified 15 form of necktie frame so designed as to completely conceal the device when the four-in-hand knot has been placed on the collar. In both the preferred and modified forms, a hinged ear is provided in which an eye is 20 located, said eye being slipped over the collar button to retain the tie and tie frame in place.

These and other objects will become apparent in the description below, in which 25 characters of reference refer to like-named parts in the drawing.

Referring briefly to the drawing, Figure 1 is a view illustrating the application of the modified type of device, both types being used in a similar manner.

Figure 2 is a front elevational view of the preferred form of necktie frame.

Figure 3 is a front elevational view of the modified type of neck tie frame.

Figure 4 is a sectional elevational view 35 taken on line 4-4 of Figure 3.

Figure 5 is a front elevational view of the preferred type of device, showing the four-in-hand knot in the process of being 40 formed.

Figure 6 is a front elevational view of the modified type of device, showing the four-in-hand in the process of being formed.

Referring in detail to the drawing, the 45 numeral 10 indicates a flat, stiff, and flexible celluloid strip. This strip is curved longitudinally to conform to the shape that a collar 11 assumes when being worn around the neck 12 of a person. A flat plate 13 of the same material is fastened to the strip 10 centrally of its length and projects somewhat from the convex edge of said strip. This plate is secured to the strip 10 by hollow rivets 14. At the lower end of the plate 50 13, openings are provided. A length of elastic cord is slipped thru the hollow rivets

14 from the back of the strip to the front, and the ends 15 of the elastic cord course downwardly and enter and pass thru the holes 16 formed in the lower end of the 60 plate 13. These ends which pass thru the holes 16 also pass thru holes in an oval ear 17 and after passing thru the holes of the ear, are knotted as indicated by the numeral 18. This oval ear is provided with a relatively large opening 19 which communicates with a vertical slot 20, the latter extending downwardly from the opening. In the preferred form of tie frame shown in Figures 2 and 5, the plate and the oval ear and the 65 method of joining said members, are identical to the modified type and the same numerals will be used to indicate the identical parts in both structures. The strip used in the preferred form is, however, radically 70 different and comprises a longitudinal strip 21 which is slightly curved transversely in order to conveniently fit between the folds of the collar 11. The end edges of the strip 21 are provided with enlarged corners 22 in 75 which open slots 23 are formed. These slots are bounded by the body of the strip 21 and extensions 24, the latter being supported in order to permit insertion of the necktie ends. Intermediate the length of 80 the strip 21 and directly above the plate 13, an elongated opening 25 is formed. The purpose for this opening will be more fully 85 hereinafter described.

When forming a four-in-hand knot about 90 the preferred type of device, the rear end of the necktie is taken and slipped thru the opening 25 from the rear. Thus the short length of the tie will extend in front of the plate 13 and ear 17, while the remainder or 95 greater portion of the length extends from the rear of the mentioned members. This greater length extending from the rear is then taken and inserted between the extensions 24 so that the width of the tie will lie 100 in the slot 25. The tie extending from the slot is then spread across the entire strip 21 and inserted in the slot 23 at the opposite end of said strip, thus covering said entire strip 21 with the exception of the portions 11 22 and 24 thereof. The end of the tie which is then at the rear of the strip 21, is folded once or twice around the plate 13 and as the end being folded arrives at the rear of the strip 21, said end is given a twist so as to 11 pass upwardly over the central portion of the strip 21 and is then turned down and

encompassed in the four-in-hand knot 26 being formed. In the modified type of device, the four-in-hand knot 27 is formed over the plate 13 in the conventional manner, and it is believed requires no description. The oval ear 17 used in both forms of necktie frames, is used in a novel manner for the purpose of securing the four-in-hand tie and necktie frame in place between the folds 10 of the collar. When ready to insert the device, the ear 17 is rotated to the position shown by the numeral 28 in Figure 4 in which position the slot 20 becomes inverted and lies above the opening 19. In 15 this position, the head of the collar button is inserted thru the opening 19 and the entire frame is permitted to slip downwardly so that the stem of the collar button is inserted into the slot 20, thus securing the 20 frame in place on the person.

I claim:

1. A necktie frame comprising a stiff and flexible strip, an elongated opening in said strip centrally of its length, open slots 25 formed at the ends of said strip, extensions on said strip adjacent the slots, a plate extending from one longitudinal side of said strip adjacent the elongated opening, hollow rivets securing said plate on the strip, said plate having openings at its lower end, an elastic cord passing thru said hollow rivets

and the openings, an oval ear having openings therein, said elastic cord passing thru the lower openings on the plate and the openings in the ear thereat being knotted, 35 said ear having an additional opening and a slot communicating with said opening, said cord permitting the rotation of said ear to a concealed position behind the plate member, the plate and strip providing a frame 40 for the forming of a four-in-hand necktie knot thereon.

2. A necktie frame comprising a stiff and resilient strip, an elongated opening in said strip, said opening extending longitudinally on the strip, the ends of said strip having transverse slots therein, said slots being closed at their ends and open intermediate their length, extensions on said strip adjacent the slots, a plate extending from one side of said strip adjacent the opening, rivets securing said plate on the strip, an oval ear having an opening therein, an elastic cord securing said ear to said strip and permitting rotation of said ear to a position behind and completely concealed by 50 said strip, said ear having a slot communicating with the opening and behind the latter.

In testimony whereof I affix my signature.

PAUL A. SCHLEMP.
